Inventor,
James W. Tufts

United States Patent Office.

JAMES W. TUFTS, OF MEDFORD, MASSACHUSETTS.

Design No. 3,816, dated January 11, 1870.

DESIGN FOR A CASING FOR SODA-WATER APPARATUS.

The Schedule referred to in these Letters Patent and making part of the same.

To all whom it may concern:

Be it known that I, JAMES W. TUFTS, of Medford, in the county of Middlesex, and State of Massachusetts, have invented and produced a new and original Design for the Casing of a Soda-Water Apparatus, of which the following is a full, clear, and exact description, reference being had to the accompanying photograph, making part of this specification.

In the photograph—

A represents the casing of a soda-water apparatus, the lower portion of which is of rectangular form, while the upper portion is so shaped as to resemble a "gambrel" roof, being inclined on both sides from *a* to *b*,

and from *b* to *c*, where it terminates in a point, the design thus produced being unique and ornamental.

Claim.

What I claim as my invention, and desire to secure by Letters Patent, is—

The design for the casing of a soda-water apparatus, herein shown and described.

JAMES W. TUFTS.
